UNITED STATES PATENT OFFICE.

JOHN J. MEYER, OF YONKERS, NEW YORK.

SPARK-PLUG.

1,079,790.

Specification of Letters Patent. Patented Nov. 25, 1913.

Application filed March 6, 1913. Serial No. 752,349.

To all whom it may concern:

Be it known that I, JOHN J. MEYER, a citizen of the United States, and a resident of Yonkers, in the county of Westchester 5 and State of New York, have invented a new and Improved Spark-Plug, of which the following is a full, clear, and exact description.

The invention relates to internal combustion engines, and its object is to provide a new and improved spark plug arranged to allow convenient and quick assembling and disassembling of the parts for removal of the electrodes for cleaning, re- 15 pairing or other purposes, and to protect the assembled parts against injury by vibration or jars incident to the running of the engine.

In order to accomplish the desired result use is made of a nipple screwing into the wall of the cylinder, a shell of insulating material removably held in the said nipple, an electrode held within the said shell, and a second electrode arranged in sparking 25 relation relative to the said first-named electrode and in contact with the said nipple, said second electrode being held exteriorly on the said shell and being removable from the nipple on removing the shell 30 from the nipple.

A practical embodiment of the invention is represented in the accompanying drawings forming a part of this specification, in which similar characters of reference indicate corresponding parts in all the views. 35

Figure 1 is a sectional side elevation of the spark plug as applied, the sleeve and electrodes being shown in elevation; Fig. 2 is an enlarged side elevation of the lower 40 end of the sleeve with one of the electrodes in position therein; Fig. 3 is an enlarged sectional side elevation of the other electrode; Fig. 4 is an enlarged side elevation of the retainer for locking the sleeve in position in the nipple; Fig. 5 is an enlarged sectional side elevation of the nipple; and Fig. 6 is a plan view of the same.

The nipple A is provided with the usual external thread A' screwing into the wall 50 B of the cylinder or other part of the internal combustion engine at which the ignition of the explosive mixture is to take place. The spark plug A is provided with a head A² of polygonal shape for convenient 55 application of a wrench or other tool to securely screw the nipple in position in the

wall B. The nipple A is provided with two bores A³ and A⁴, of which the lower portion A³ is somewhat less in diameter than the upper or outer bore A⁴, and an annular seat A⁵ is formed intermediate the adjacent ends of the bores A³, A⁴. Within the bores A³, A⁴ of the nipple A extends a sleeve C of porcelain or other suitable insulating material, and within the sleeve C is held an electrode D extending at its ends beyond the ends of the sleeve C, the upper end being provided with the usual fastening means E for attaching a conductor F to the electrode D. The lower end of the electrode D is in sparking relation with an electrode G, and this electrode G is provided with a ring or band G' encircling the lower portion of the sleeve C. The upper end of the band G' is provided with an outwardly-extending flange G² seated on the seat A⁵ of the nipple A so as to make firm contact with the nipple A thus providing engine contact for sparking. The top of the flange G² is engaged by a cushion H on which 75 is seated a collar C' formed integrally on the sleeve C and fitting into the upper or larger bore A⁴. The cushion H is preferably made of superimposed washers of 80 conducting and non-conducting materials, the 85 conducting washers alternating with the non-conducting washers.

A retainer I is connected with the upper end of the nipple A to securely lock the sleeve C in position in the nipple A. The 90 retainer I forms with the upper end of the nipple A a breech block type of joint to permit of quickly inserting the retainer I in the upper end of the nipple A by a turn less than a complete turn, it being understood that for this purpose the lower portion of the retainer I is provided with a mutilated or interrupted thread I' adapted to engage a correspondingly shaped mutilated or interrupted thread A⁶ in the upper 95 portion of the bore A⁴ (see Figs. 4, 5 and 6). The retainer I is provided with a head I² having recesses I³ in its peripheral face for application of a rod, spanner wrench, or other tool for convenient unscrewing or screwing 100 up the retainer I in the nipple A. The washer J is preferably interposed between the lower end of the retainer I on top of the collar C' to provide a cushion between the retainer and the sleeve to avoid injury to the sleeve C on screwing up the retainer I. The upper portion of the retainer I is provided with a 105

gasket K encircling the sleeve C to provide another cushion between the sleeve and the said retainer.

It will be noticed that when the retainer I is removed from the nipple A the sleeve C can be readily pulled out of the nipple A and with it both electrodes D and G without disturbing the position of the nipple A in the wall of the cylinder. It is understood 10 that when the sleeve is removed from the nipple A and with it the electrodes D and G then the latter can be readily cleaned of soot or other extraneous matter or repaired in case it is necessary to do so. In replacing the sleeve C and the electrodes D and G it is only necessary to reinsert the sleeve C so that the flange G² is seated on the seat A⁵, and then the operator screws up the retainer I to securely lock the sleeve C in 20 position in the nipple A.

By the arrangement described the electrodes D and G are held at all times in proper sparking relation with each other, and the sleeve and electrodes can be very 25 quickly removed for cleaning, repairing and other purposes, and replaced and securely locked in position. It will further be noticed by the arrangement set forth that a very good contact is had between the electrode G and the nipple A owing to the annular flange G² being seated on the annular seat A⁵. Injury to the parts incident to 30 shocks and jars is prevented owing to the use of the cushions H, J and K.

35 The spark plug shown and described is very simple and durable in construction and composed of comparatively few parts, not easily liable to get out of order.

It will be noticed that the gap between the electrodes D and G can be examined and 40 adjusted without removing the nipple A. On screwing the retainer I up or down, the sleeve C resting on the cushion H is caused to move up and down correspondingly and in doing so the electrode D moves up and 45 down relative to the electrode G, but as the electrode D is made of sufficient length the necessary gap between the electrodes D and G is maintained.

Having thus described my invention, I 50 claim as new and desire to secure by Letters Patent:

A spark plug, comprising a nipple provided with an interior seat, a sleeve of insulating material removably held within the 55 said nipple, the sleeve having a collar and a cylindrical lower portion, an electrode within the said sleeve and extending below the said reduced lower portion, a second electrode in sparking relation with the said 60 first-named electrode and provided with a cylindrical band having a flange seated on the said nipple seat, the said band fitting onto the said lower portion of the said sleeve, and a cushion interposed between the 65 said electrode flange and the collar of the said sleeve, and a screw retainer screwing in the said nipple against the said sleeve collar.

In testimony whereof I have signed my 70 name to this specification in the presence of two subscribing witnesses.

JOHN J. MEYER.
